UNITED STATES PATENT OFFICE

2,563,129

WIRE STRETCHER DEVICE

Henry Milton Montgomery, Wichita, Kans.

Application December 3, 1948, Serial No. 63,253

2 Claims. (Cl. 254—163)

1

My invention relates to an improvement in wire stretching devices and refers more particularly to a type of stretcher for use in stretching clothes lines. An object of my improved stretcher is to provide a device of the kind mentioned that is simple, easy and inexpensive to make and buy.

A further object of the invention is to provide a device of the kind mentioned that is extremely effective in its work, one that is exceptionally strong, long lived and durable as well as being neat in appearance. These and other objects will be more fully described and explained as this description progresses.

Now referring to the accompanying drawings in which similar numerals of reference designate the same parts throughout the several figures of the drawings:

Fig. 1 is a top plan view of my improved stretcher.

Fig. 2 is a side view of the stretcher, the view being as seen from the line II—II in Fig. 1, and looking in the direction of the arrows.

Fig. 3 is a side view of the stretcher, the view being as seen from the line III—III in Fig. 1, and looking in the direction of the arrows.

Fig. 4 is a front view of the stretcher, parts being broken away for convenience of illustration.

Fig. 5 is a rear view of the stretcher device.

Fig. 6 is a perspective view of the stretcher.

Fig. 7 is a top plan view of a portion of a clothes line cross bar of a clothes line post and showing my improved stretcher mounted thereon and having one end of a clothes line attached thereto in position for being stretched by the stretcher.

In the drawings the stretcher device is shown as having a U-shaped frame 10. The central portion of the loop portion of the U has a hole 11 therethrough for attachment purposes as will later be described. The outer end of each leg 12 and 13 are provided with aligned and registering holes 14 and 15.

Between the legs 12 and 13 and in axial alignment with the holes 14 and 15 is a tubular element, a piece of pipe 16, the inside diameter of which is slightly less than that of the holes 14 and 15.

A square bar 17 is loosely passed through and is revolvable in the holes 14 and 15 and is tightly pressed in and through the tube 16 so that the ends of the bar 17 project beyond the outside face of each leg of the U-shaped frame 10. The tube 16 and bar 17 having been thus assembled between and through the legs 12 and 13 of the U-shaped frame 10, holes 18, 19 and 20 are drilled

through one end of the tube 16 and square bar 17 to provide an aligned passage for the reception of one end of a clothes line wire 21 which may be wrapped around or wound on the tube 16 for stretching purposes as will later be described.

The device is provided with a ratchet plate 22, one end of which is pivotally mounted on the frame leg 13 at the point 23. The other end of 10 the ratchet plate 22 is provided with a right angle notch 24 that is adapted to receive and fit the square corners of the bar 17 to prevent clockwise rotation of the bar 17 and tube 16.

In Fig. 7 is shown a cross bar 25 of a clothes line post indicated by the dotted circle 26. A plurality of wire stretchers may be attached to the cross bar 25 for stretching several lines. The stretchers are attached to the cross bar 25 by passing a bolt 27 through the hole 11 in the U-shaped frame 10 and then passing the bolt 27 through holes in the cross bar 25 and then threading a nut 28 on the bolt 27 to rigidly bind and hold the stretcher on the cross bar 25.

The stretcher having been mounted on the 25 cross bar 25 as above described, one end of a clothes line wire 21 may be inserted in and through the holes 18, 19 and 20 whereupon a wrench 29 may be placed on either end of the square bar 17 whereby the bar 17 and tube 16 30 may be revolved in a counterclockwise direction to wind the line 21 on the tube 16 to stretch the line 21. As the bar 17 and tube 16 are revolved the corners of the bar 17 and tube 16 are 35 revolved, the corners of the bar 17 will raise the adjacent end of the ratchet plate 22 and as the rotation of the bar 17 continues the ratchet plate 22 will fall to its original position as shown in Fig. 6 to hold the bar 17 and tube 16 against clockwise rotation and hold the line 21 in a 40 stretched condition.

While the device as shown and described is probably the preferred form of the device, it is to be understood that such modifications of the device may be employed as lie within the scope 45 of the appended claims without departing from the spirit and intention of the invention. Now having fully shown and described my invention, what I claim is:

1. In a clothes line stretcher device of the kind described; said device having a U-shaped frame, and means in said frame for attaching the frame to a supporting element therefor, a winding reel, said reel comprising a round tubular element and a multisided bar pressed through the tube so that 55 the corners of the bar tightly engage the inside

3

circular surface of the tube, said bar being longer than the tube, said tube being loosely positioned between the ends of the legs of the U-shaped frame, said multisided bar being revolvably carried in circular openings in the outer ends of the U-shaped frame and projecting beyond the outer faces of the legs of the said U-shaped frame, a ratchet plate, said ratchet plate being pivotally carried on the outside of one of said U-shaped frame legs and being engageable with the corner 10 portions of said multisided bar for preventing the rotation of said bar and tube in one direction only.

2. In a clothes line stretcher device of the kind described; the structure defined in claim 1, said tubular element and multisided bar having registering holes therethrough to receive the end of a clothes line wire as a means of first securing 15

the wire to the winding assembly of the device and second to prevent possible turning of the multisided bar in the said tubular element.

HENRY MILTON MONTGOMERY.
